UNITED STATES PATENT OFFICE.

ANDREW COCHRAN, OF PHILADELPHIA, PA., ASSIGNOR TO WILLIAM E. MONTAGUE AND THOMAS E. WHITE, BOTH OF SAME PLACE.

DESIGN FOR A CARPET.

SPECIFICATION forming part of Design No. 14,529, dated January 1, 1884.

Application filed November 1, 1883. Term of patent 3½ years.

To all whom it may concern:

Be it known that I, ANDREW COCHRAN, a citizen of the United States, and a resident of Philadelphia, Pennsylvania, have invented a new and original Design for a Carpet-Pattern, of which the following is a specification.

My design is shown in the accompanying print, and comprises, mainly, the five figures A, B, D, E, and F. The figure F is shown entire; but only one-fourth of each of the figures A, B, D, and E is shown, the remaining three-quarters of each figure being similar to that shown. Each of the figures A, B, D, and E comprises a center piece and a border. The center pieces of the figures A and B are of a geometrical character, and the borders comprise leaves, twigs, and blossoms; but the center pieces of the figures D and E are mainly

of a floral character, and the borders comprise both leaves and geometrical figures. The figure F is inclosed by the remaining figures of the pattern, is of an oblong shape, and comprises a leaf, a flower, and scroll-like ornamentation of a character too fully shown to need detailed description. 20

I claim—

The design for a carpet-pattern, said design comprising the figures A, B, D, E, and F, all substantially as shown and described.

In testimony whereof I have signed my name 30 to this specification in the presence of two subscribing witnesses.

ANDREW COCHRAN.
